UNITED STATES PATENT OFFICE.

ALONZO M. FOSTER, OF CABOT, VERMONT.

DESIGN FOR A SAP-SPOUT.

SPECIFICATION forming part of Design No. 23,392, dated June 19, 1894.

Application filed May 14, 1894. Serial No. 511,252. Term of patent 7 years.

To all whom it may concern:

Be it known that I, ALONZO M. FOSTER, a citizen of the United States, residing at Cabot, in the county of Washington and State of Vermont, have invented and produced a new and original Design for Sap-Spouts, of which the following is a specification, reference being had therein to the accompanying drawing.

The object of this design is to provide a sap spout that will be both useful and ornamental. A perspective view of the same is shown in the accompanying drawing, in which—

A is the spout, having a bucket hook B set at a slight departure from a right angle to the central line of the spout, and a hook C above the same. The spout is represented as open along a portion of its upper side. At the outer or front end of the spout is a bead E from which depends the teat F, while the rear

end is squared or flattened on all sides, said flattened portions being curved or round at the end where they join the circular part of the spout. Above the hook B is a bead G running around the spout and down to the 25 hook B.

The leading ornamental features of my design are the beads E and G and the squared rear end having its flattened portions curved where they join the circular part of the spout. 30

What I claim as new is—

The design for a sap spout, substantially as herein shown and described.

In testimony whereof I affix my signature in presence of two witnesses.

ALONZO M. FOSTER.
